INTERLOCKING ELECTRICAL CONNECTOR

Fletcher E. Maxwell, Glendale, Calif.

Application July 11, 1949, Serial No. 104,067

9 Claims. (Cl. 173—330)

1

This invention relates to so-called socket connectors for electrical conductors and particularly to an improved form thereof in which the connecting elements are interlocked with each other incident to completion of the electrical connection.

An object of the invention is to provide a plug and socket type of electrical conductor connecting means which is so constructed and arranged that the elements are first inserted one within the other and given a relatively rotary movement to effect the electrical connection.

Another object of the invention is to provide a plug and socket type of connector for electrical conductors in which the wall socket portion is so constructed and arranged that it may be installed in a conventional outlet box in the same manner as conventional wall socket units.

Still another object of the invention is to provide a plug element which is adapted for use with the above wall socket and which, further, is so constructed and arranged that two conductors may be interconnected with identical plugs.

A still further object of the invention is to provide a plug and socket type of connecting means for electrical conductors in which the live contact point is shielded to prevent accidental contact therewith.

Still another object of the invention is to provide a plug and socket type of connecting means for electrical conductors in which the two elements to be connected have identical, semi-circular mating projections and socket portions and having the contact elements housed or guarded by the semi-circular projections in such manner that the contacts are interengaged by relative rotation of the connecting elements.

Still another object of the invention is to provide a connecting means for electrical conductors comprising a wall socket element and a plug type element which may be engaged with said wall socket or with an identical plug element.

A still further object of the invention is to provide a connecting means adapted to connect plugs and sockets of the type comprising the present invention with conventional screw type plugs and sockets.

Still another object of the invention is to provide a connecting means for electrical conductors in which the above enumerated objects are achieved and which is simple and economical to manufacture and install and which is both safe and reliable in use.

With the above objects in view, together with such other objects and advantages as may subsequently appear, the invention resides in the

2

parts, and in the construction, combination and arrangement of parts described, by way of example, in the following specification and illustrated, also by way of example in the accompanying drawings which form a part of said specification and in which drawings:

Fig. 1 is a front elevation of a wall socket assembly embodying the invention.

Fig. 2 is an enlarged, sectional top plan view taken on the line 2—2 of Fig. 1.

Fig. 3 is a front elevation of a wall socket assembly mounted in a conventional outlet box.

Fig. 4 is a side elevation of the wall socket assembly; the associated outlet box being shown in section on the line 4—4 of Fig. 3.

Fig. 5 is a rear, sectional elevation taken on the lines 5—5 of Figs. 2 and 4.

Figs. 6 and 7 are side elevations of the mating faces of the contact carrying assemblies of the wall socket structure as indicated by the arrows 6—6 and 7—7, respectively, on Fig. 5.

Fig. 8 is an exploded view of the component parts of one of the contact carrying assemblies; the parts being shown in front elevation.

Figs. 9 and 10 are sectional front elevations on the lines 9—9 and 10—10 of Fig. 2, respectively, showing the upper socket of the wall socket open and the lower socket engaged by a plug element and the inter-engagement of the plug and socket contact elements.

Fig. 11 is a contact end elevation of a plug element adapted for cooperation either with the socket assembly shown in Figs. 1 to 10, inclusive, or with another plug having identical contact means.

Fig. 12 is a side elevation, partly in section, of the plug shown in Fig. 11.

Fig. 13 is an opposite end elevation of the plug shown in Figs. 11 and 12.

Fig. 14 is a side elevation of the contact carrying assembly of the plug; the view being taken from the same direction as Fig. 12.

Fig. 15 is an end elevation of the assembly shown in Fig. 14, showing the conductor attaching means carried by the contact elements.

Figs. 16 and 17 are side elevations of the mating faces of the component parts of the contact assembly of the plug.

Figs. 18 and 19 are transverse sectional views taken on the lines 18—18 and 19—19 of Fig. 12, respectively.

Fig. 20 is a socket end elevation of an adapter having at one end a contact means such as employed in the present invention and at the other a conventional internally threaded socket to receive a lamp or the like.

Fig. 21 is a medial sectional elevation taken on the line 19—19 of Fig. 20,

Fig. 22 is a medial section taken on the line 22—22 of Fig. 21,

Fig. 23 is an elevation of the externally threaded end of another form of adapter,

Fig. 24 is a medial elevation taken on the line 24—24 of Fig. 23,

Fig. 25 is a medial section taken on the line 25—25 of Fig. 24,

Fig. 26 is a side elevation showing the endwise relative movement incident to the interengagement of two identical plugs; partly completed portions of the casing elements of the plugs being broken away for clearness of illustration, and

Fig. 27 is a view similar to Fig. 25 but showing both the endwise and rotative movements completed.

Referring first to Figs. 1 to 10 inclusive there is shown a wall socket assembly adapted for use in conventional outlet boxes. The assembly is mounted in a wall W including a studding W' having an outlet box B mounted thereon by a nail or screw N. Leads L and L' extend through a conduit C to the outlet box and are secured to the binding post screws P and P' of the assembly. The front of the assembly is covered by a conventional cover plate F, having the usual openings formed therein and which is secured in place by means to be later described in detail.

The socket assembly per se is formed of non-conductive material and a thin rectangular base member 1 having recessed side portions 2—2 and having a rib 3 rising from one face thereof around its sides except where interrupted by the recesses 2—2, a combined contact carrying and shield element 4, a side wall element 5 and a second side-wall and contact carrying element 6; all of said elements having interfitting faces so arranged as to hold them in alignment for mounting in an outlet box. The sides of said members 5 and 6 are each provided with clearance spaces 5a and 6a, respectively, disposed in alignment with the recesses 2—2 in the base member 1. The mounting means comprises a U-shaped metal strap 7 having out-turned perforated end portions 8—8 adapted to be secured to the usual in-turned ear portions E of the outlet box by screws S threaded into the ear portions E, E of the outlet box (see Fig. 4). A screw S having its head adjacent the strap 7 and passing therethrough and thence through aligned holes 10, 11, 12 and 13 in the members 1, 4, 5 and 6, respectively, and thence through a hole in the center of the cover plate F and engaged by a nut 9' at the exterior of the cover plate serves to hold the socket assembly together and secured to the strap 7.

The member 6 rests on and extends along one side of the base plate 1 and on its rear face is provided with a recess 14 into which the locating rib 3 extends (see Fig. 2) and the outer side face and the ends of the member are in alignment with the corresponding side and end edges of the base plate. The rear face of the member is provided with a groove 15 to receive a contact member 16 one end of which carries the binding post screw P' and the contact portion of which is bifurcated and includes outwardly extending shanks 17 and 18 which terminate in laterally extending contact portions 17' and 18' disposed within vertically disposed recesses 19 and 20 formed in semi-circular bosses 21 and 22 at the outer face of the member 6. Spaced from the curved portion of the periphery of the bosses 21 and 22 are skirt portions 23 and 24, respectively,

the outer ends of which extend through one side of each of the openings O in the coverplate F and the grooves 25 and 26 between the adjacent faces of the respective bosses and skirt portions are adapted to receive annular flange portions of the plug assemblies used with these sockets as will be later described in detail. In rear of the bosses 21 and 22, the member is cut away to form recesses 27 and 28 of segmental outline adapted to receive a portion of the cooperating plug element incident to rotation of the plug element after insertion into the socket in the manner to be later described. Preferably, the element 6 is moulded from a suitable plastic or ceramic material with the contact member moulded in place.

The rear face of the element 4 rests on and covers all of the surface of the base member 1 not covered by the element 6 and is provided with a groove 29 which mates with the rib 3 on the base member. On the edge thereof adjacent the element 6 the element 4 carries two inverted L-shaped members 30 and 31 disposed so that one face thereof lies against the flat side face of each of the bosses 21 and 22 as best shown in Figs. 3 and 9, and the shank portions cover the grooves in the member 6 in which the shanks 17 and 18 of the contact members 17' and 18' are housed as shown in Fig. 10. The outer, wider portions of the members 30 and 31 are each provided with narrow rectangular slots 32 and 33 disposed opposite the contact member recesses 19 and 20 in the element 6 and are so disposed that a contact element on a plug will enter through the slot and engage the contact element in the element 6 upon rotation of the plug as will later be described. Also extending outwardly from the base member 4 at an acute angle to each of the members 30 and 31 are thin wall members 34 and 35 so disposed that one flat side thereof lies against the walls 36 and 37 of the recesses 27 and 28.

The element 4 is preferably moulded and is formed from non-conductive material and has incorporated therein a bifurcated conductor 38 carrying the binding post P at the juncture of the two arms 39 and 40 thereof. The arm 39 extends along and flush with the rear face of the element 4 to a point 41 opposite the mid width of the member 34 and thence extends directly to the outer face of that member, thence parallel to and along the face of the member 34 and across the end thereof and terminates in a contact portion 42 which lies at about the middle of the recess 27 and which is spaced from and curved about the axis of the socket. The arm 40 extends directly to the mid width portion of the member 35 and thence along the outer face and across the end of the member 35 and terminates in a contact portion 43 which is similarly disposed in the recess 28. It will be noted in Fig. 8 that the free ends of the contact portions do not extend beyond the faces of the L-shaped members 30 and 31 which are remote from the members 34 and 35.

The element 5 has a flat inner face 44 adapted to rest on the outer face of the element 4 and is provided with dowels 45 adapted to engage holes 46 in the member 4 to hold the two elements in alignment. The element is formed with larger and smaller circular surfaces 47 and 48 which are generated about the same centers as the grooves 25 and 26 and which form ledges 49 and 50 at the same level as the bottom of the grooves. These curved surfaces together with the adjacent faces of the members 30 and 31 form semicircular sockets 51 and 52 adapted

to receive the plugs for which these sockets are adapted. Additionally, the element 5 includes curved outwardly projecting skirt portions 53 and 54 which project through the cover plate F at the sides of the socket openings, opposite the skirt portions 23 and 24, respectively.

Between the sockets 51 and 52 the element 5 is provided with a laterally extending tongue portion 55 through which the hole 12 extends and the member 6 is provided with an oppositely laterally projecting tongue portion 56 which overlies the tongue portion 55 and through which the hole 13 extends. Also, each end face of the element is provided with laterally extending tongues 57 and 58 which engage suitable notches 59 and 60 in the ends of the element 5 to assist in holding the several parts of the socket in alignment for insertion of the screw 9. Thus through the various interlocking faces including the rib 3 on the base plate 1, the mating grooves 14 and 20 on the elements 6 and 4, the dowels 45 on the element 5 engaging the holes 46 on the element 4, the meeting faces of the elements 4, 5 and 6 together with the tongues and grooves on the ends thereof make it possible for the entire assembly to be held together for assembly with the strap 7 and screw 9. At the same time, the conducting elements 16 and 38 are completely insulated from each other and are covered except for the various contact points and the necessarily exposed binding post portions. The wall socket assembly is the same size as conventional wall socket assemblies, and is installed in conventional outlet boxes in the conventional manner. The binding posts are located in the conventional position so that no special skill is required to make the installation.

Referring now to the plug assembly portion of the invention and particularly to Figs. 11 to 19, inclusive there is shown a plug adapted to be attached to a light cord or similar conductor and to be connected to and disconnected from a wall socket assembly of the type above described or to be connected to or disconnected from an identical plug assembly. The plug assembly includes a cylindrical casing 61 formed of non-conductive material having at one end a reduced diameter bore 62 through which the end of the conductor extends for attachment to the binding posts. Mounted in the larger bore 63 of the casing is the contact carrying and shielding assembly comprising elements 64 and 65 which have semicircular body portions 66 and 67 which, when the elements are assembled, combine to form a circular outline that fits snugly within the bore 63 and to rest against the end wall 68.

The element 64 at its inner end is formed with two segmental recesses 69 and 70 divided by a centrally disposed wall member 71 and the inner end of the element 65 is provided with similar recesses 69' and 70' divided by a similar wall member 71' and when the two elements are assembled, these recesses combine to form sector-shaped housings for the binding post ends of the contact members 72 and 73 separated by the wall members 71 and 71' (see Figs. 15 and 16); portions of the wall members extending through the bore 62 to separate the leads of the cord to which the plug is attached.

The element 64 includes a sector shaped portion 74 which extends beyond the end of the casing 61 and this portion 64 from about the plane of the end of the casing to a point within the

casing is undercut to provide a recess 75 through the sidewall 76 of which the contact end 77 of the contact member 72 projects (see Figs. 16 and 18). The element 64 is provided with a groove 78 which leads from the recess 69 parallel to the axis of the plug thence angularly laterally to a second parallel portion and thence at right angles to and through the wall 76 and in this groove the contact member 72 is loosely positioned (see Figs. 16 and 18). The contact member 73 extends from the binding post cavity 79, 79' along a groove 79 formed in the member 64 and extending parallel to the length thereof and terminating in a laterally disposed sector-shaped recess 80 in which the contact portion 81 of the member 73 is disposed (see Figs. 16 and 19).

The element 65 is generally similar to the element 64 from the binding post end to a point even with the inner wall 82 of the recess 75 and from that point extends outwardly as a thin inverted L-shaped portion 83 the outer face of which intersects the axis of the plug assembly and the inner face of which overlies and covers the grooves 78 and 79 and the recess 80 except for a rectangular opening 84 opposite the recess 80 for the entrance of a contact point of another plug or socket. The elements 64 and 65 with the contact members 72 and 73 are held in assembled relation by dowels 85 and 86 on the member 64 which engage corresponding holes 87 and 88 in the meeting face of the member 65 (see Fig. 14) and the assembly is then placed in the casing 61 and secured therein by a screw 89 which extends through holes 90 and 91 in the members 64 and 65 and is threaded into the opposite wall of the casing at 92 (see Fig. 12).

The mode of effecting a connection between the plug and socket is illustrated in the lower portions of Figs. 9 and 10. The plug is first inserted endwise into the socket with the semicircular portion thereof entering the corresponding portion of the socket and with the semi-circular boss 22 of the member 6 entering the corresponding socket or clearance portion of the plug; the groove 26 receiving the skirt portion 93 of the plug casing to permit this endwise movement. The plug is then rotated clockwise as viewed in these figures and upon such movement the contact point 77 on the plug will enter the slot 33 in the member 31 and engage the contact point 18'. Simultaneously, the member 83 will move over the end of the contact point 43 bringing the contact point 81 into engagement therewith to complete the electrical connection. It is to be noted that when thus engaged the plug and socket are interlocked and can not be separated without first rotating the plug to effect breaking the circuit. In installation of the socket it is preferable that the "hot" wire be connected to the binding post P' so that the "hot" contact points 17' and 18' associated therewith are those that are shielded by the members 30 and 31. It will be further appreciated that this novel construction permits the direct interconnection of identical plugs since the semi-circular projections of each will enter the semi-circular recesses of the other whereupon relative rotation of the plugs (see Figs. 26 and 27) will interlock the plugs with incident interengagement of the contacts 77 and 81 of one plug with the contacts 81 and 77 respectively of the other plug. It will be appreciated that in preparing cords having these plugs at each end, if the contacts are reversely connected to the conductors, the safety

feature of having the "hot" contact shielded will be preserved.

Referring now to Figs. 20, 21 and 22, there is shown an adapter to connect a plug of the type forming part of the present invention with a conventional internally threaded socket such as a lamp socket. In this form of the invention the internally threaded metal shell 94 is moulded in place in a cylinder or casing 95 having a wall portion 95' extending across it intermediate its ends. The shell 94 has a laterally extending tongue portion 96 through which a rivet 97 disposed in the wall 95' extends and the other end of the rivet is engaged by the out-turned end 98 of the contact element 99 which is generally similar to the element 72 in the previously described form of plug assembly. A second rivet 100 extending through the wall 95' at a point diametrically opposite the rivet 97 secures a contact element 101 adapted to engage the center contact of a light bulb or other connecting element screwed into the shell 94 and at the opposite side of the wall 95' the rivet 100 is engaged by the out-turned end 102 of a contact element 103 which is generally similar to the contact element 73 in the plug assembly shown in Figs. 11 to 19. The members 104 and 105 in which the contact elements 99 and 103 are housed are generally similar to the members 64 and 65, respectively, except that the portions that formed the cavities for the binding posts and the dividing wall between the cavities are dispensed with. A screw 106 extending through one wall of the casing 95 thence through holes 107 and 108 in the members 104 and 105 and threadedly engaging the opposite wall of the casing holds the parts in assembly.

Referring now to Figs. 23, 24 and 25, there is shown an adaptation of the plug element of the present invention to an externally threaded plug for engaging the conventional type of screw threaded socket. In the form shown, an externally threaded sleeve 109 is molded in place on a casing member 110 which is in the form of a hollow cylinder having a larger diameter portion 111 at one end and a smaller diameter portion 112 at the other end which terminates in an end wall 113. The outer face of this end wall is provided with two diametrically opposite notches or recesses 114 and 115 into one of which a laterally extending tongue portion 116 of the sleeve 109 extends and is engaged by a rivet 117 extending through the end wall 113. A contact element 118 having a portion thereof extending over the center of the end wall 113 is disposed in the recess 115 and secured therein by a rivet 119 mounted in the end wall 113. The contact assembly is similar to that shown in Figs. 20, 21 and 22 except that the contact elements 120 and 121 are formed with extensions having S-shaped bends formed therein terminating in out-turned portions 122 and 123 so that they will engage the heads of the rivets 119 and 117 respectively, with sufficient pressure to insure proper contact. The parts are held in assembly by the screw 106 in the same manner as shown in Figs. 20, 21 and 22.

While in the foregoing specification I have described a specific mode of execution of my invention, it will be understood that this is by way of example and that I do not intend thereby to be limited to the exact form disclosed and that the invention embraces all such modifications of the parts and of the construction, combination and arrangement of parts as shall come within the purview of the appended claims.

I claim:

1. A connector for electrical conductors comprising a pair of assemblies having identical interengaging and contact effecting elements; each 5 of said assemblies comprising a semi-cylindrical plug portion and a plug receiving socket having a plug receiving opening disposed with the flat side thereof in juxtaposition to the flat side of said plug; said plug within said opening being reduced segmentally in cross section with resultant 10 increase of said socket to segmental form of greater than semi-circular extent, a first contact member projecting into said socket, a second contact member housed within said plug and terminating in a contact surface adjacent the outer 15 end of said plug, and an opening in a side wall of said plug opposite said contact surface through which said first contact member of one of said assemblies may enter and engage said contact surface of the other assembly when said assemblies are interengaged with the plug portion of each assembly disposed in the socket portion of the other assembly.

2. A plug and socket connected means for electrical conductors comprising a wall socket assembly adapted to be mounted in a conventional outlet box and having a pair of binding posts for connecting it to a source of electrical energy and having a base portion supporting a plurality of 20 sockets for engagement with connector plugs, each of said sockets including a semi-cylindrical plug receiving recess and a semi-cylindrical plug portion disposed with its flat side forming the flat side of said semi-cylindrical recess; each of said 25 plug portions adjacent the bottom of said semi-cylindrical recess being cut away to form a segmental shaped recess, a plurality of contact members disposed one in each of said segmental shaped recesses connected to one of said binding posts 30 and a plurality of contact members disposed one in each of said semi-cylindrical plug portions and connected to the other of said binding posts, and a plug element constructed and arranged to engage 35 said sockets.

3. A plug and socket connector means for electrical conductors comprising a plug element having a pair of binding posts for connection to the leads of a lamp cord or the like at one end thereof and having a semi-cylindrical recess at the 40 other end with a semi-cylindrical plug portion disposed adjacent to said recess with the flat side of said plug portion forming the flat side of said recess; said plug portion adjacent the bottom end of said semi-cylindrical recess being cut away to 45 form a segmental shaped recess, a contact member connected to one of said binding posts and extending into said segmental shaped recess, a second contact member connected to the other of said binding posts and extending into said semi-cylindrical plug portion, and a slot in the flat side face of said plug portion affording access whereby 50 a contact member of another connecting means may enter for engagement with said second contact member.

4. A plug and socket connector means for electrical conductors comprising a wall socket assembly adapted to be mounted in a conventional outlet box and having a pair of binding posts for connecting it to a source of electrical energy, 55 said assembly comprising a base plate, having a peripheral rib, a contact carrying member having a thin base portion engaging the rib on said base plate and a pair of inverted L-shaped flange portions 60 lying in planes intersecting the planes of said

inverted L-shaped flange portions at acute angles, a contact element carrying one of said binding posts mounted on said contact carrying element and having contact points overlying said smaller flanges, a socket forming element mounted on the base of said contact carrying element and having curved wall portions which cooperate with said inverted L-shaped flanges to define semi-cylindrical recesses, a second contact carrying element mounted on the base plate adjacent to said first contact carrying member and said socket forming element and engaging the rib on said base plate; said second contact carrying member having face portions which mate with the outer surfaces of said flanges, a contact element carrying said other binding post mounted in said second contact carrying member and having contact portions housed in recesses in said mating faces, a slot in each of said inverted L-shaped flanges opposite said last named contact points and a screw passing through said base plate, both of said contact carrying members and said socket forming member effective to hold said members in assembled relation, and a detachable plug having corresponding semi-cylindrical plug and socket means adapted to be connected with and disconnected from said assembly.

5. A plug and socket connector means for electrical conductors comprising a wall socket assembly adapted to be mounted in a conventional outlet box and having a pair of binding posts for connecting it to a source of electrical energy, said assembly comprising a base plate, having a peripheral rib, a contact carrying member having a thin base portion engaging the rib on said base plate and a pair of inverted L-shaped flange portions and a pair of shorter flange portions lying in planes intersecting the planes of said inverted L-shaped flange portions at acute angles, a contact element carrying one of said binding posts mounted on said contact carrying element and having contact points overlying said smaller flanges, a socket forming element mounted on the base of said contact carrying element and having curved wall portions which cooperate with said inverted L-shaped flanges to define semi-cylindrical recesses, a second contact carrying element mounted on the base plate adjacent to said first contact carrying member and said socket forming element and engaging the rib on said base plate; said second contact carrying member having sector shaped plug forming portions, the flat faces of which mate with the faces of said inverted L-shaped portions to form semi-cylindrical plug portions of the substantially same cross-sectional area as said sockets, a contact element carrying said other binding post mounted in said second contact carrying member and having contact portions housed in recesses in said sector-shaped portions, a slot in each of said inverted L-shaped flanges opposite said last named contact points and a screw passing through said base plate, both of said contact carrying members and said socket forming member effective to hold said members in assembled relation, and a detachable plug having corresponding semi-cylindrical plug and socket means adapted to be connected with and disconnected from said assembly.

6. A plug and socket connector means for electrical conductors comprising a cylindrical, non conductive casing element having a transverse wall portion intermediate its ends, an internally threaded metal sleeve mounted in one end of said casing having a laterally extending portion engaged by a rivet extending through said wall por-

tion, a contact element mounted on said wall portion by a second rivet extending through said wall portion at a point remote from said first named rivet and having a portion thereof disposed at the center of said end wall, connecting means at the other end of said casing comprising two members having semi-circular base portions disposed in said casing and secured in said casing by a screw extending diametrically across said casing and both of said base portions; one of said members having a sector-shaped portion extending beyond said casing and having a segmental shaped recess formed therein adjacent said base portion, a first contact member mounted in a groove in said one member having one end in engagement with one of said rivets and the other end extending into said segmental shaped recess, a second contact member mounted in a second groove in said one member having one end in engagement with the other of said rivets and having the other end thereof disposed in a sector shaped recess in said sector shaped portion, the other of said members having a flange portion of inverted L-shape disposed with one side thereof adjacent the flat face of said one member; said inverted L-shaped portion covering the grooves in said one member and having a slot formed therein opposite said sector shaped recess to admit a contact of another connecting assembly for engagement with contact portion in said recess; said sector shaped portion of said one member and said inverted L-shaped flange of said second member together forming a plug portion of semi-cylindrical cross section and the space between the wall of said casing and the side of said flange forming a semi-cylindrical recess of substantially equal cross section adapted to engage a connecting element having identically disposed sockets, and plug elements.

7. A plug and socket connector means for electrical conductors comprising a cylindrical shell having a reduced diameter opening at one end for entrance of a conductor and having inserted from the other end two members having semi-cylindrical base portions secured therein by a screw extending diametrically across said casing and said base portions, one of said members having a sector shaped portion extending beyond said casing and having a segmental-shaped recess formed therein adjacent the base portion of said member, a first contact member mounted in a groove in said one member, a contact member disposed in said groove and extending from a binding post carried by said contact member adjacent said reduced diameter opening along said groove and terminating in a contact point disposed in said segmental shaped recess, a second groove in said one member, a second contact member disposed in said second groove and extending from a binding post carried by said second contact member adjacent said reduced diameter opening along said second groove and terminating in a contact portion disposed in a recess in said sector shaped portion; the other of said members having a flange portion of inverted L-shape disposed with one side thereof adjacent the flat face of said one member; said inverted L-shaped portion covering the grooves in said one member and having a slot formed therein opposite said sector shaped recess to admit a contact of another connecting assembly for engagement with contact portion in said recess; said sector shaped portion of said one member and said inverted L-shaped flange of said second member together forming a plug portion of semi-cylindrical

cross section and the space between the wall of said casting and the side of said flange forming a semi-cylindrical recess of substantially equal cross section adapted to engage a connecting element having identically disposed sockets, and plug elements.

8. A connector means for electrical conductors comprising two assemblies each having a pair of contact elements including means for attachment to a pair of conductors, each of said assemblies having a semi-cylindrical plug portion and an adjacent semi-cylindrical socket portion, having an end wall; the curved faces of said portions being generated about a common axis and the plug portion of each assembly being insertable into the socket portion of the other assembly; each of said plug portions having a segmental shaped recess cut in one side thereof; said recess extending from the plane of said end wall axially of said plug portion to a point slightly in excess of the length of said plug portion; one of said contact members in each of said assemblies terminating in a contact point projecting into said segmental shaped recess and the other of said contact members terminating in a recess formed in the outer end of said plug portion and positioned to be engaged by the first named contact member of the other assembly when the two assemblies are inserted one within the other and given a relative rotative movement; the segmental shaped recesses of each assembly providing clearance space for that portion of each of the plug portions which overlie the said recesses and certain of the interengaging faces of said plug portions and said recesses when interengaged serving to absorb all stresses incident to forces tending to separate said assemblies by direct pull parallel to said axis.

9. A connector for electrical conductors comprising a pair of assemblies having identical interlocking and contact effecting elements; each of said assemblies comprising a semi-cylindrical plug portion and a plug receiving socket having

a semi-cylindrical plug receiving opening disposed with the flat side thereof in juxtaposition to the flat side of said plug portion; said plug portion within said opening being reduced segmentally in cross section with resultant increase of said socket to segmental form of greater than semi-circular extent, a first contact member having an electrical contact effecting surface disposed in said socket and lying in a plane normal to the axis about which the curved surface of said plug portion is generated, a second contact member having an electrical contact effecting surface disposed wholly within said plug and lying in a plane parallel to the plane of said first contact member, and an opening in a wall of said plug portion opposite said second named contact surface through which said first named contact member may enter and bring said contact effecting surfaces together when said assemblies are interengaged with the plug portion of each disposed in the socket of the other and subjected to relative rotation; the entry of said first contact members into said openings in said plug walls serving to interlock said assemblies against separation while said contact surfaces are interengaged.

FLETCHER E. MAXWELL.
